UNITED STATES PATENT OFFICE.

CHARLES J. APPLETON, OF RAVENSWOOD, NEW YORK.

OVERSEAMING SEWING-MACHINE.

SPECIFICATION forming part of Letters Patent No. 680,013, dated August 6, 1901.

Application filed July 10, 1900. Serial No. 23,112. (No model.)

To all whom it may concern:

Be it known that I, CHARLES J. APPLETON, a citizen of the United States, residing at Ravenswood, in the county of Queens, State of New York, have invented certain new and useful Improvements in Overseaming Sewing-Machines, of which the following is a specification, reference being had to the accompanying drawings.

10 My invention relates to overseaming sewing-machines, and more particularly to that type of such machines designed to form an overedge seam particularly adapted for sewing knitted fabrics, although it is evident it 15 may be employed for sewing fabrics of any character.

The objects of my present invention are to provide mechanism whereby an even and uniform overedge seam may be rapidly produced by three separate and interlooped threads, the parts being further so constructed and arranged that the noise usually incident to the movement of numerous parts is greatly diminished.

25 With these general objects in view my invention consists of the parts and combinations as will be hereinafter more fully described, and definitely pointed out in the claims.

30 In the drawings, Figure 1 is a longitudinal section of a sewing-machine embodying my invention. Fig. 2 is a cross-section of the same on the line xx , Fig. 1. Fig. 3 is a cross-section of the same on the line yy , Fig. 1. Fig. 4 is a cross-section of the same on the line zz of said figure, and Fig. 5 is an enlarged detail elevation of a portion of the head and connected parts.

35 The bed-frame A is preferably formed as an inclosing casing for the moving parts to be described and has on its upper surface the usual work-plate A', which may constitute a continuation of the upper surface of the casing. Rising from the bed-frame A is the upright A², carrying at its upper end the arm A³, in which is suitably journaled in any usual form of bearings a a' the main driving-shaft A⁴, which at its outer end is provided with the usual band-pulley A⁵ and hand-wheel A⁶. Suitably journaled in the bed-frame A in any usual or desired form of bearings b b' is the shaft B, which is driven from

the main driving-shaft A⁴ by means of the eccentrics a² a³ and b² b³ on said shafts A⁴ and B, respectively, through the eccentric- 55 rods B' B², as will be fully understood from Fig. 1.

Mounted so as to have free reciprocating movement in the bearings c c', formed in the head C, is the needle-bar C', which is given 60 reciprocating movement from the main driving-shaft A⁴ through the link c², one end of which is connected to a stud carried by the sleeve c³, secured to the needle-bar, and the other end of which engages a crank-pin c⁴, 65 secured to the eccentric fast on the main driving-shaft, as will hereinafter more fully appear. The said needle-bar carries the usual needle c⁵ and thread-guide c⁶.

Secured to the shaft B in any approved 70 manner are the face-cams D and E, each of which is provided with a cam-groove d and e, respectively, of desired or required contour to impart to the lower and circular needles to be described the necessary motions. Mounted 75 to oscillate on the stud D' is the lower-needle bar F, carrying at its upper free end the needle f, provided, preferably, with a thread-eye f'. Secured to the lower-needle bar F is a projecting arm F', preferably provided at 80 its end with a rounded portion f², adapted to be seated in a block d², which travels in the cam-groove of the cam D. The form of the said cam-groove is such that the lower-needle bar F is oscillated on its stud D' as the 85 cam D revolves to cause the needle f to reciprocate forward and backward below the work-plate past the line of travel of the vertical needle c⁵.

Mounted to oscillate on the stud E', secured 90 to the bed-frame A, is what I term the "circular-needle" bar G, carrying at its free end the circular needle g, preferably, though not necessarily, curved slightly and provided with a thread-carrying eye g' near its end. 95 Projecting from the circular-needle bar, preferably at its opposite end, is an arm G', provided with a rounded bearing g², adapted to be seated in a correspondingly-shaped socket g³ in a block g⁴, freely movable in the cam-groove e of the cam E. The shape of the cam-groove e is such and the parts are so disposed 100 that the circular needle g is caused to reciprocate in a path above and below the work-

plate and over the edge of the fabric, as will more fully appear.

Thread is supplied to the vertical needle c^5 from the spool H , being passed from said spool through the guide-eye h , around any usual form of tension h' , through the guide-eye h^6 and guide-slot c^6 in the needle-bar, over the pins $h^2 h^3$, and through guide-eye h^6 to the eye of the vertical needle. Between the pins $h^2 h^3$ the thread is looped under the end h^5 of a slack take-up h^4 , preferably shown as a coiled spring, one end of which is secured to the machine-head at h^7 , as will clearly appear from Fig. 2.

Each of the needles f and g are also supplied with a separate thread, the same being led to each of said needles from any convenient or suitable source of supply, (not necessary to illustrate,) and from such supply the threads each pass through any usual or preferred form of take-up—such, for instance, as shown for the thread leading to needle f in Fig. 2—wherein i is a lug fixed to the bed-frame and having a thread-eye in its end, and i' is a lever pivoted at i^8 and having at its free end a thread-eye i^2 . In order to take up the slack thread, as during the reciprocation of the needle f , I secure to the shaft B an eccentric i^4 and connect the lever i^2 thereto by an eccentric-strap i^5 , whereby as the shaft rotates the lever i' is moved to and from the fixed lug i . A similar take-up is shown in Fig. 1 for the thread leading to the needle g , wherein i^{10} is the fixed lug provided with an eye, as above described. i^{11} is the lever having an eye in its end, said lever being moved to and from the fixed lug i^{10} by the eccentric i^{14} and strap i^{15} in the same manner as described for the similar take-up shown in Fig. 2.

From the construction thus far shown it will be noted that the vertical needle c^5 is reciprocated as usual, that the lower needle f , carried by the lower-needle bar F , is reciprocated across or close to the path traversed by the vertical needle c^5 , said lower needle, however, always remaining below the work-plate of the machine, and that the circular needle g is by its connection with the cam E reciprocated across or close to the path of the lower needle f below the work-plate and also across or close to the path of the vertical needle c^5 , the motion of the circular needle being such that it passes above and below the work-plate at each reciprocation over or around the edge 55 of the fabric being sewed. The relation and timing of parts are such that in each complete cycle of movements in forming the complete stitch over the edge of the fabric the lower needle f is caused to advance into position shown in Fig. 1, in which position it forms a loop or opening between itself and the thread carried thereby, through which loop the circular needle g passes, said circular needle then continuing its movement and carrying 60 its own thread to form a loop through which the vertical needle c^5 passes as the latter descends. Prior to the descent of the vertical

needle c^5 the lower needle f has retreated from its advanced position shown in Fig. 1, and just prior to the ascent of the said vertical needle the lower needle passes through the loop formed in the thread carried by the vertical needle. The circular needle in the meantime also retreats below the work-plate, ready to pass through the next loop formed by the advancing lower needle. Thus it will 70 seem that the loop of the vertical-needle thread is engaged by the lower needle below the material being stitched and that the loop of the lower-needle thread is engaged by the circular-needle thread, whose loop in turn passes over the edge of the fabric and is engaged by the vertical-needle thread.

I have designated the different needles as “vertical,” “circular,” and “lower” in order 85 to distinguish between them; but it is not to be understood that such terms designate any particular form or character of needle other than that it is such to permit each needle to carry a separate and independent thread.

Coöperating with the stitch-forming mechanism thus described I have provided a form of feed comprising a four-motion foot, as will more fully appear, which, however, forms no part of my present invention.

Mounted in suitable bearings $k k'$, secured to the bed-frame A , is a short shaft K , provided with eccentrics $k^2 k^2$, which through the eccentrics $k^3 k^3$ on the shaft B and any usual form of eccentric-straps $k^4 k^4$ and rods k^5 is 90 driven from the said shaft B . The shafts K and B , at a point beneath the work-plate and subadjacent the opening therein for feed-foot L' , are each provided with an eccentric l and l'' , respectively, which eccentrics are 95 embraced by the slotted ends l^2 and l^3 of the feed-block L , carrying the feed-foot l' , secured thereto, as by the screws or pins l^4 . It will be noted that the slotted ends of the feed-block are elongated and that in one of 100 said slotted ends is fitted a bearing-block l^5 , normally pressed against the eccentric l by the spring l^6 . Thus while the feed-block is caused to move in consonance with the eccentrics a yielding action is afforded the feed-block 105 as it moves in the feeding direction, and a set-screw L' is provided to regulate the extent of the feeding motion. It will thus be seen that the feed-block at its serrated foot l' has four motions imparted to it—viz., a motion from 110 front to rear of the machine when the feed-foot is in upper feeding position, a downward movement at the end of its feeding action, a forward movement when in lower or non-feeding position, and a rising movement from the 115 non-feeding to the feeding position—and that the spring l^6 and screw L' permit adjustment of the feeding action to a greater or less extent, as desired, while the spring permits the feed-block to yield under any undue stress thereon 120 in feeding the fabric. Above and coöperating with the feed-block L and feed-foot l' is the 125 presser-foot m , carried by a presser-arm M , having a slot m' near one end, through which 130

passes a pin m^2 , secured to the machine-head, the latter being provided with a slot or recess m^3 , preferably having a rounded form to permit the said arm M to swing to a limited extent around the pin m^2 as a center. The lower portion of the head is slotted, as at m^4 , to permit the lower end of the arm M free swinging movement. The lower portion of the arm M , as at m^5 , is preferably reduced in diameter and is engaged by the arm o , carried by an adjustable sleeve o' , secured to the eccentric-arm O , and interposed between the abutment m^6 and the under side of arm o is a spring m^7 , normally tending to press the presser-foot m downward. Secured to the main driving-shaft A^4 within the arm A^3 is the double eccentric C^2 , provided with the crank-pin c^4 and having the eccentric portions p and p' , the former of which is embraced by the upper end of the eccentric-arm O . Said arm O , near its lower end, is provided with a slot o^2 , which is engaged by a pin o^3 , secured to the machine-head. From this construction it will be evident that as the main driving-shaft revolves the eccentric portion p of the double eccentric C^2 will impart to the eccentric-arm O a rising-and-falling movement as well as a swinging movement from side to side, and since the eccentric-arm O is connected to the presser-arm M in the manner shown and described it will be evident that the said arm and the presser-foot carried thereby will be given like movement—viz., a rearward movement in the lower or feeding position, an upward movement at the end of the feeding action, a forward movement in the upper or non-feeding position, and a downward movement at the end of the said forward movement. It is also evident that the spring m^7 , while yieldingly holding the presser-foot m upon the fabric, will yet permit it to rise to adjust itself to varying thicknesses of fabric.

In overedge seaming, especially of knitted goods, it is desirable that the edges of the fabric shall first be evenly cut, and to this end I may provide any usual form of cutter, that in the present instance comprising a blade s , carried by the lower end of a sliding bar S , movable in the machine-head, as shown, the said bar, and consequently the knife s , being given the shearing or rising-and-falling action by the portion p' of the eccentric C^2 , which is embraced by a link S' , connected at S^2 to the sliding bar S .

It will be noticed that as the connections for transmitting motion from one shaft to another I have employed eccentrics and straps, which, being adjusted properly, avoid all noise and shocks incidental to usual crank connections, and this same is true also with respect to the feed-block and its operating parts.

Having thus described my invention, what I claim, and desire to secure by Letters Patent, is—

1. In an overedge sewing-machine, the combination of a vertical needle and means to reciprocate it, a lower needle and means to reciprocate it below the work-plate of the ma-

chine, a circular needle and means to reciprocate it above and below said work-plate over the edge of a fabric, each of said needles carrying a thread, and a slack take-up for each of said threads, said slack take-up for the lower and circular needles comprising a fixed eye, a movable arm provided with an eye, and an eccentric for moving said movable arm. 75

2. In an overedge sewing-machine, the combination of a vertical needle and means to reciprocate it, a lower and a circular needle, needle-bars each carrying one of said needles and pivoted to the frame of the machine, a shaft journaled in said frame and carrying cams, the faces of which are disposed opposite each other, the said lower and circular needle bars being extended beyond their pivotal connection with the frame to engage said cams to be thereby positively moved as described. 85

3. In an overedge sewing-machine, the combination of a vertical needle and means to reciprocate it, a lower and a circular needle, 90 needle-bars each carrying one of said needles and pivoted to the machine-frame, a shaft journaled in the machine-frame and carrying two face-cams, the faces whereof are disposed opposite to each other, and blocks movable 95 in the cam-groove in the face of cams, the said lower and circular needle bars being extended beyond their pivotal connection with the machine-frame to engage said blocks in the face-cams. 100

4. In an overedge sewing-machine, the combination of a vertical needle and means to reciprocate it, a lower and a circular needle, needle-bars each carrying one of said needles, a shaft journaled in the machine-frame and carrying cams for directly engaging and operating said lower and circular needle bars, one of said needle-bars being pivoted to the frame below said shaft, and the other of said needle-bars being pivoted to the frame above 110 said shaft, and each of said bars being extended beyond their pivotal connection with the frame to engage one of said cams carried by the shaft. 115

5. In an overedge sewing-machine, the combination of a vertical needle and means to reciprocate it, a lower and a circular needle, needle-bars each carrying one of said needles and pivoted to the frame of the machine, a shaft journaled in said frame and carrying 120 cams, the faces of which are disposed opposite each other, the said needle-bars being extended beyond their pivotal connection with the frame to engage said cams to be thereby positively moved as described, and an independent take-up for the threads carried by said needles. 125

In testimony whereof I have signed my name to this specification in the presence of two subscribing witnesses.

CHARLES J. APPLETON.
